UNITED STATES PATENT OFFICE

2,353,242

HIGH-TENSION FUSE ASSEMBLY AND
HEATER THEREFOR

Tomlinson F. Johnson, Atlanta, Ga.

Application September 24, 1942, Serial No. 459,567

3 Claims. (Cl. 200—127)

This invention relates to high tension fuses of the type used on transmission systems to cut off the current due to overloads or abnormal currents and, among other objects, aims to provide a relatively simple and effective heater associated with the fuse assembly to keep the fuse lead wire and fuse element dry and thereby prevent undue corrosion induced by corona effect within the tube. The main idea is to provide a very cheap and effective heater element employing eddy currents or induced currents within the heater and so arranged that it will produce sufficient heat to keep the atmosphere within the tube relatively dry since it has been found that corona around the fuse lead promotes deterioration very much more rapidly when the humidity is relatively high within the tube.

Other aims and advantages of the invention will appear in the specification, when considered in connection with the accompanying drawing, 20 wherein:

Fig. 1 is a longitudinal sectional view of a fuse tube assembly embodying one form of the invention;

Fig. 2 is a cross sectional view taken on the line 2—2 of Fig. 1;

Fig. 3 is a longitudinal sectional view of a portion of a fuse tube showing a modified heater;

Fig. 4 is a longitudinal sectional view of a portion of the fuse tube showing a further modified heater; and

Fig. 5 is a sectional view similar to Figs. 3 and 4 but showing still another modified form of heater.

Referring particularly to the drawing, the type of fuse assembly selected for illustrative purposes is generally similar to that shown in my Patent No. 2,230,955 issued February 4, 1941, which discloses such a fuse employed in a drop-out fuse assembly; although it may be like that shown in my Patent No. 2,269,372 issued January 6, 1942, or any other type. Furthermore, such fuses may be of the stationary type in which the fuse leads are ejected from the tube. In such fuse assemblies, it has been found that corona eats the fuse leads and ultimately destroys them, the rate of destruction being roughly proportional to the moisture content of the air around the leads and to the voltage. In accordance with this invention, the eddy currents around the fuse lead are employed to produce sufficient heat to keep the air relatively dry within the fuse tube.

Referring now to the drawing, for a clear understanding of the invention, it is sufficient to state that the fuse assembly comprises an in-

sulating tube 10 carrying upper and lower contact members 11 and 12 respectively, the lower contact member being articulated so that the fuse assembly can drop out as disclosed in my aforesaid 5 Patent No. 2,230,955. The upper contact member is provided with a fuse receiving opening 13 through which is threaded the usual fuse element having a button member 14 and a fusible section 15 to which is connected a flexible lead 16 10 extending downwardly through the tube and electrically connected to the lower contact element 12. When the fuse blows, due to overload, it will be understood that the fuse lead is ejected from the tube through the lower end. As shown, the 15 fuse lead is spaced from the inner wall 17 of the fuse tube, although this is not essential.

In Figs. 1 and 2, there is shown a heater element in the form of a metal sleeve or tube 18 composed of magnetic material, preferably iron, and insulated from the fuse lead by an insulating coating or covering 19 applied on the fuse lead 16, the arrangement being such that the eddy currents around the fuse lead will cause induced current to flow around or in the heating tube and heat it by resistance sufficiently to keep the lead 16 dry. This heater 18 maintains a higher temperature within the tube 10 than the atmospheric temperature on the outside. It has been found that a relatively thin sleeve or tube 30 of iron only a few inches long and arranged in the lower portion of the fuse tube will serve the purpose, maintaining the temperature above, say, one hundred degrees within the tube. It will be understood by those skilled in the art that the 35 amount of heat generated in the iron tube will depend upon the current flowing in the fuse lead, the length of the iron tube, its cross sectional area and the composition of the iron or resistance offered by the iron or other metal of which it 40 is made.

Actual demonstrations have shown that a heater applied to a fuse assembly in this manner has greatly prolonged the life of fuse leads by practically eliminating the destructive effect of 45 corona. In fact, the heater reduces the destructive effect to a point where it is no longer a source of trouble. Thus, it reduces the cost of maintenance and relieves linemen of the necessity of making very frequent inspections and replacing the vital fuse parts which are relatively expensive. Even in the enclosed type of fuse lead, considerable moisture trouble is experienced due to sweating of the fuse lead, which is obviated by the heater.

55 It is also within the scope of this invention

to provide as a heater, a resistance, in series with the fuse lead, as shown in Fig. 5. For this heater the current passing through the fuse lead 30 also passes through a short resistance wire section 31 which becomes slightly heated to thus heat the inside of the fuse tube 20 and the lead wire. The resistance wire is preferably round in cross section and is brazed or otherwise secured in series with the flexible lead wire. This particular type of heater is especially useful in fuse assemblies carrying small currents.

Fig. 3 shows a further modified heater in the form of a cylindrical metal tube section 21 against the inside wall of the fuse tube 20, which is held in place in a counterbored portion 22 of the tube 20 by means of a set screw 23. This tube 21, as well as the sleeve 18, may be made of iron or steel, as well as any one of a number of high-resistance alloys which are well known in the art. As an example of the size of a heater tube, the heater 21 may be two and one-half inches long and one-sixteenth of an inch thick.

The form of heater shown in Fig. 4 is of the transformer type having an iron tube 24 in the counterbored portion 25 of the fuse tube 20. A cylindrical layer 26 of insulation separates the tube 26 from a short-circuited coil 27. A sleeve 28 retains the tube 24 in place and this sleeve is held in place by a screw 29.

If the heater is in the form of a short-circuited coil of high-resistance wire, it can be effective with twenty-five turns, for instance, assuming that two and one-half amperes of current are flowing in the fuse lead. This will raise the temperature of the fuse lead 30°, which is more than is required to produce the desired results. As a matter of fact, a few degrees above surrounding air temperature is all that is necessary.

Obviously, the invention is not limited to the particular forms thereof herein shown and described, but is capable of embodiment in various combinations and subcombinations.

5 I claim:

1. In a high tension, expulsion fuse assembly of the character described, wherein a fusible link is located near the upper end of an insulating tube and a long, flexible lead wire, constituting the current conductor, is connected to the fusible element and extends through the lower end of the tube so that it is exposed to the corrosive action of corona and moist air within the tube, an electric heater element associated with said lead wire 10 at a distance from the fuse link utilizing current derived from the lead wire to heat it slightly within the confines of the tube and serving the sole purpose of preventing water of condensation from collecting on and corroding the lead wire, 15 without influencing the rupture of the fusible link due to an over-load.

2. In a high tension, expulsion fuse assembly, as set forth in claim 1, wherein the electric heater element is of the induction type and is located 20 within the tube.

3. In a high tension fuse assembly comprising an insulating tube carrying a fusible element and a flexible lead wire connected thereto and projecting through one end of the tube, an induction heater of the transformer type within the fuse tube around the lead wire and remote from the fusible element to heat the lead wire to a temperature slightly above that of the atmosphere and thereby prevent water of condensation from 30 collecting thereon.

TOMLINSON F. JOHNSON.
